(57) **CLAIM**

The ornamental design for an earphone charging case, as shown and described.

DESCRIPTION

1. Earphone charging case
- 1.1 : Perspective of the first configuration
- 1.2 : Front of the first configuration
- 1.3 : Rear of the first configuration
- 1.4 : Left of the first configuration
- 1.5 : Right of the first configuration
- 1.6 : Top of the first configuration
- 1.7 : Bottom of the first configuration
- 1.8 : Perspective of the first configuration
- 1.9 : Reference view
- 1.10 : Perspective of the second configuration
- 1.11 : Front of the second configuration
- 1.12 : Rear of the second configuration
- 1.13 : Left of the second configuration
- 1.14 : Right of the second configuration
- 1.15 : Top of the second configuration
- 1.16 : Bottom of the second configuration
- 1.17 : Perspective of the second configuration

(Continued)

The dash-dash broken lines in the drawings depict the portions of the earphone charging case which form no part of the claimed design.
